UNITED STATES PATENT OFFICE.

JOHN STOGDELL STOKES, OF MOORESTOWN, NEW JERSEY.

SEALED-WRAPPED PACKAGE.

1,219,788.

Specification of Letters Patent. Patented Mar. 20, 1917.

Application filed June 2, 1916. Serial No. 101,258.

To all whom it may concern:

Be it known that I, JOHN STOGDELL STOKES, a citizen of the United States, residing at Moorestown, in the county of Burlington and State of New Jersey, have invented certain new and useful Improvements in Sealed-Wrapped Packages, of which the following is a specification.

This invention relates to a sealed wrapped package of that character wherein a cover or wrapper is employed which completely envelops the box or container in such manner as to effectively exclude air, moisture, vermin and foreign matter which might tend to injure or destroy the contents.

While the ordinary sealed wrapped or tight wrapped package is very effective so far as the protection of the contents or goods is concerned, it usually possesses the disadvantage that the wrapper or cover completely conceals the joints, seams or other sections of the box which are intended to be ruptured or broken for the purpose of permitting the removal of the contents, and the result is that in opening one of these tight wrapped packages it is usually necessary to employ a knife to cut away parts or portions of the walls, for, in instances where the walls are merely broken away by the person, there is always present the liability of breaking or tearing too much of the wall or walls with the result that it is practically impossible to thereafter effectively close the package so as to exclude air, moisture and foreign matter.

In carrying out the present invention, I propose to provide a sealed wrapped package which when in its completely sealed and closed form, while effectively excluding the admission of air, moisture and foreign matter, and while presenting a smooth, neat appearance, it will also possess the advantage that it is so constructed as to not only indicate what portion or section of the box is to be grasped and manipulated to open the same, but such portion or section of the box will provide an effective means for actually enabling the box cover to be opened, and at the same time when the desired portion of the contents have been removed from the box or container, the cover may again be closed to protect the remaining contents.

Still a further object of the invention is the provision of a package of this character having a cover section provided with a flange which is adapted to overlie the outer

face of one of the walls of the box or container, so that even though this flange be completely covered and sealed by a wrapper, it will protrude or extend sufficiently beyond the wall to indicate its location and to enable it to be grasped by a person to break open or lift such cover when it is desired to obtain access to the contents of the box.

Still a further object of the invention is the provision of a package of this character wherein the box or container proper is made of a one-piece blank with the rear wall of the box constituting a hinge member carrying the cover section of the box, such cover having depending marginal flanges at the front and side edges thereof, the front marginal edge being adapted to overlie the top portion of the outer face of the front of the box, while the side flanges are adapted to fit against the inner faces of the sides of the box. Thus, when completely enveloped in a tightly adhering or sealed wrapper, the front of the cover will constitute an indication and a means for enabling the box to be readily opened, while when closed, the entire box will present a neat, smooth and attractive appearance.

With the above recited objects and others of a similar nature in view my invention consists in the construction and arrangement of parts set forth in and falling within the scope of the appended claims.

In the accompanying drawings,

Figure 1 is a plan view of a blank from which the box proper is to be preferably made.

Fig. 2 is a perspective view of a box made from the blank such as is shown in Fig. 1, said box being illustrated as partially open.

Fig. 3 is a perspective view of the completely closed box.

Fig. 4 is a perspective view of a cover or wrapper blank and of the box, and showing the latter about to be positioned upon the wrapper blank.

Figs. 5, 6, 7, and 8 are perspective views showing different steps or stages of the application of the wrapper or cover blank.

Fig. 9 is a perspective view of the complete sealed wrapped package.

Referring now to the accompanying drawings in detail, the letter A indicates the box blank as an entirety, this blank being made of cardboard, box-board, paste-board or other suitable material. The main body portion of the blank is substantially rectangu-

lar in shape and is scored longitudinally on parallel lines, as shown at 1, and is then scored transversely along the lines 2, so that when folded along the scored lines to form the box shown in Fig. 2, the end sections 3 of the blank form the front of the box, the section 4 of the blank constitutes the bottom of the box while the end wings 5 of the blank form the ends of the box, these end wings of course being integral with and extending from the section 4 of the blank. The back of the box which also constitutes a hinge is formed from the section 6 of the blank, while the section 7 of such blank constitutes the top or lid of the box and is integral with the hinge back 6, this section 7 having a front lap 8 which forms a front depending flange for the cover, and side laps 9 which form the depending side flanges of the cover. When the blank, such as is shown in Fig. 1, has been bent into box-like form, such as is shown in Fig. 2, the front covers of the box are preferably stayed by triangular stay strips 10. The meeting corners of the laps 8 and 9 of the blank are preferably cut away as at 11, so that when these laps are bent along their scored lines to form the flanges of the box cover, corner spaces or gaps will exist which will remove the surplus material and which will enable the flanges 9 to be tucked in against the adjacent end walls of the box when the box is closed while the front flange 8 may fit over the front wall of the box as shown in Fig. 3.

When the box has been filled with the desired goods, it is preferably completely wrapped in a cover, a blank of which is shown in Fig. 4. This blank is indicated as an entirety by the letter B, and the inner face thereof is completely coated with a suitable adhesive or paste, as shown at C. The blank is divided into sections by the parallel longitudinal score lines 12 and the transverse score lines 13. The closed box is first preferably placed upon the bottom section 14 of the cover blank and pressed against the same to cause the blank to adhere to the bottom of the box. The front and rear sections 15 and 16 of the blank are then folded up against the front and back of the box as shown in Fig. 5. The marginal end laps 17 of the bottom of the cover blank are then folded inward against the end walls 5 of the box, as shown in Fig. 6, and subsequently the end laps 18 of the front section of the blank are also folded inward against the end walls of the box, as shown in Fig. 7. The marginal edge strip 20 of the cover blank may now be folded down against the top or lid 20 of the box and the end tabs 21 of this marginal strip folded down against the adjacent end laps 18 at the ends of the box, as shown in Fig. 8. The top section 22 of the cover blank is now folded downward and pressed 65 against the cover or lid of the box and the

end wings 23 which are preferably of the same area as the ends of the package are pressed downward and inward against the ends of the box so that the package is completely covered and enveloped, as shown in Fig. 9 when the cover blank has been caused to firmly and smoothly adhere thereto by suitable pressure.

Of course I have above described but one form of cover or wrapper blank and but one manner of applying the same to the box, in order to illustrate the invention, but it will be readily understood that the cover blank may be of a different form and may be applied to the closed box in any suitable manner, so long as it tightly and closely fits the same or completely envelops and seals the box so as to give the package substantially the appearance shown in Fig. 9.

When the package has been wrapped and sealed, as shown in Fig. 9, the contents will be preserved in the condition in which they were originally placed in the box for a long period of time, inasmuch as air, moisture and foreign matter will be excluded therefrom. It will be noted, however, that inasmuch as the front flange 8 of the cover overlaps and projects beyond the front wall of the box it will form a longitudinally extending shoulder or ledge as indicated at 24, and this ledge will exist and be apparent even though the thin wrapper or cover overlies the same. Thus, when it is desired to open the box, it is merely necessary for a person to run the thumb-nail or finger-nail along the shoulder 24, thus ripping or breaking the wrapper paper, and then grasp the flange 8 and pull upward upon the same, this will open the cover and in the act of opening the cover the material of the wrapper will be severed or broken at the top end edges of the box, and of course if desired, the back wall or hinge section of the box may also be broken down, although this is usually not necessary. After the required contents have been removed from the box, if desired, the cover may again be closed down against the same to protect the remainder of the contents.

Furthermore, it will be noted that the depth of the shoulder formed by the front flange 8 of the cover is accentuated to some degree by the fact that the end portions of the flange overlie or bear against the adjacent sides of the stay strips 10, as shown in Fig. 3, and therefore the flange 8 is held away from the front wall 3 of the box by substantially the thickness of these sides of the stay strips.

While I have herein shown and described one particular embodiment of my invention, I wish it to be understood that I do not confine myself to all the precise details of construction herein set forth by way of illustration, as modification and variation may 125 130 135

be made without departing from the spirit of the invention or exceeding the scope of the appended claims.

What I claim is:

- 5 1. A sealed wrapped package comprising a box formed from a single blank of material bent to provide a bottom section, a rigid front wall and rigid end walls, a back wall constituting a hinge for the box and a lid or
- 10 cover formed integral with the back wall and having a depending flange at its front longitudinal marginal edge, such flange overlying the outer face of the front wall of the box, and a wrapper adhesively attached
- 15 to and completely enveloping the box, the lower edge of the depending flange which overlies the front wall of the box forming a severing edge along which the wrapper may be cut, such depending flange of itself constituting a gripping means for enabling the box to be opened.
- 20 2. A sealed wrapped package comprising a box formed of a single blank of material and constituting a bottom section, a rigid front wall and rigid end walls, vertical stay strips at the meeting points of the front and end walls, a back wall for the box also constituting a hinge member and a lid or cover formed integral with the back wall of the
- 25 box, said lid or cover having a depending front flange and depending end flanges, said front flange extending beyond the outer face
- 30

of the front wall of the box the end portions of such front flange of the cover contacting with the adjacent portions of the stay strips, 35 whereby said front flange forms a pronounced shoulder in conjunction with the front wall of the box, and a wrapper completely enveloping the box when closed and adhesively attached to said box at all sides 40 to form a tight covering therefor, and adapted to be severed along the lower edge of the front flange.

3. A sealed wrapped package comprising a body portion of a box and a cover integral 45 with the body portion of the box and having end flanges fitting against the inner faces of the end walls of the box and a front flange overlying and extending beyond the front wall of the box, and a wrapper completely 50 enveloping the box and adhesively attached to all of the walls of the box, the front flange of the cover forming a shoulder in conjunction with the front wall of the box, and constituting an indicating and severing edge for 55 that portion of the wrapper which is to be ruptured or severed to permit the opening of the box.

In testimony whereof I affix my signature in the presence of two witnesses.

JOHN STOGDELL STOKES.
